UNITED STATES PATENT OFFICE.

GEORGE E. WARREN, OF SWAMPSMOTT, MASSACHUSETTS, ASSIGNOR TO UNITED SHOE MACHINERY CORPORATION, OF PATERSON, NEW JERSEY, A CORPORATION OF NEW JERSEY.

HEEL.

Application filed August 20, 1923, Serial No. 658,292. Renewed March 8, 1926.

This invention relates to shoe heels and is aimed at the improvement of heels of the cushion, or resilient, type with a view to the production of a heel capable of easy and perfect attachment to a shoe with important economies in both material and labor costs.

It is a common practice to provide a shoe with a heel comprising a resilient section, usually of rubber, having a thickness less than the entire height of the heel in the finished shoe, combined with a comparatively rigid base section consisting of one or more leather lifts and a rand. Such a base section presents a flat outer face for engagement with the rubber heel section and, to secure the best results, it is customary to gouge or scoop out the middle portion of that face of the base which engages the heel seat portion of the shoe. This is rendered necessary, if a perfect fit is to be secured, by the fact that the degree of convexity of the heel seat is greater than can be readily compensated for by the concavity produced by the application of a rand alone to the flat surface of a base lift. The labor cost of producing commercial rubber heel bases is high and a considerable waste of material necessarily occurs.

The present invention provides a novel heel in which, for the first time a flat tread face and tight edge joints are secured without the use of cement by associating a concavo-convex base section, with a deformable, resilient top section which is normally concavo-convex but is of such form that when it is drawn down into close engagement with the base section it will present a substantially flat tread surface. In the illustrated form of the invention the resilient top section is thicker at the edges than in the middle and its concave attaching face is rendered inextensible by a fabric or equivalent reinforcing element so that, when its tread face is deformed to flatness, an extremely tight edge joint is produced. The maximum results may be secured if the deformable heel section is of such shape that it is normally concavo-convex on every line of cross section, and in the illustrated heel it is so formed, but the substantial benefits of the invention may be secured by using concavo-convex deformable sections of other than this exact shape.

The concavo-convex base section may ad-

vantageously be of scoop-shape and is preferably of uniform thickness throughout, whereby there is no waste of material and the difficult and expensive operations of rand forming and base gouging are eliminated.

The scope of the invention further includes a resilient heel alone which is especially adapted to produce a flat tread surface and a tight edge joint, without cement, when attached to a convex surface, such a heel being of concavo-convex form, thicker at the edges than in the middle, and having a nail anchoring portion at its concave face which is substantially inextensible. This feature of the invention may be regarded as in the nature of an improvement upon the heel disclosed and claimed broadly in a copending application of the present inventor filed December 26, 1922, Serial No. 608,908.

The above and other features and advantages of the invention will be fully understood and appreciated from reading the following detailed description of one embodiment thereof, in connection with the accompanying drawing, in which

Fig. 1 is a perspective view, partly in section, showing the heel end of a shoe with a base section attached thereto and a rubber top section located upon the base, ready to be flattened;

Fig. 2 is a longitudinal central section through the base and top section of the heel;

Fig. 3 is a view partly in elevation and partly in section looking toward the breast face of the heel; and

Fig. 4 is a view similar to Fig. 1 but showing the heel finally attached.

The shoe 10, in the illustrated embodiment of the invention, has a short outersole 12 which may be similar to that disclosed in my copending application, Serial No. 476,659, filed June 11, 1921. The heel base 14 may comprise one or more short lifts 16 and one or more full length lifts 18 and differs essentially from the usual plano-concave heel base in that it is concavo-convex in cross section and, in the illustrated embodiment of the invention, is substantially scoop-shaped, the concave face of the base being of a shape to conform closely to the convex surface of the heel seat of the shoe.

The heel base 14 may be of substantially

uniform thickness throughout, consisting of plain lifts assembled and molded in a heel compressor to the desired scoop shape. The manufacture of such a base involves no waste of the material of the lifts and requires but few simple operations.

In the illustrated example of the invention the base 14 is attached to the heel seat of the shoe by nails 20 driven from the inside of the 10 shoe and clinched at the outer face of the base section. Jig holes, indicated at 22, may conveniently be employed to facilitate the positioning of the various parts in proper relation to each other as described in detail and 15 claimed in my copending application Serial No. 476,659, filed June 11, 1921, hereinbefore referred to.

The resilient top section 24 is normally concavo-convex on every line of cross section 20 and, as herein shown, is thicker at the edges than in the middle, being so proportioned that when it is pressed down upon the base section 14 the tread face of the heel will be deformed to flatness. At the concave face 25 of the top section 24 is a nail anchoring portion 26 which may conveniently consist of one or more plies of fabric vulcanized to the rubber body of the top section of the heel. The fabric renders the attaching face of the 30 rubber heel 24 substantially inextensible so that when the heel is flattened upon the base 14 all of the rubber at any substantial distance from its attaching face is compressed, the heel thus being sufficiently stiffened to 35 produce a very tight edge joint without the use of cement.

The rubber heel is flattened upon the base by pressure and attached by nails 28 driven through the rubber until their heads are 40 seated upon the nail holding insert 26. The rubber closes over the heads of these attaching nails and a suitably roughened or corrugated area 30 covering that part of the tread face of the heel through which the nails are 45 driven makes the marks left by the nails and drivers practically invisible.

Although the invention is herein shown and described as applied to a shoe with a short 50 outersole, it should be understood that it is equally applicable to shoes with full length soles and that the same advantages are realized in that case as in the case of the shoe illustrated in the drawings.

Having disclosed the invention, what is

claimed as new and desired to be secured by 55 Letters Patent is:—

1. A shoe heel comprising a deformable, resilient top section which is normally concavo-convex on every line of cross section, flattened and combined with a comparatively 60 rigid concavo-convex base section, the heel as a whole having a flat tread face and a concave seat face.

2. A shoe heel comprising a deformable, resilient top section which is normally concavo-convex and thicker at the edges than in 65 the middle, flattened and combined with a comparatively rigid concavo-convex base section.

3. A shoe heel comprising a deformable, 70 resilient top section which is normally concavo-convex on every line of cross section and thicker at the edges than in the middle, combined with a comparatively rigid scoop-shaped base section of substantially uniform 75 thickness throughout, to produce a flat tread face and a concave, scoop-shaped face conforming to the heel seat of a shoe.

4. A deformable, resilient heel normally of concavo-convex form, thicker at the edges 80 than in the middle, and having at its concave face a nail anchoring portion which is substantially inextensible and is at least as large as the nailing area.

5. A deformable heel normally of concavo-convex form on every line of cross section comprising a principal body portion of 85 resilient material, and a fabric nail anchoring element permanently united to said body portion at the concave attaching face of the heel, so constructed and arranged that attaching 90 nails driven through the nail anchoring element will hold the heel with its entire attaching face substantially in engagement with a convex surface to which it is attached and 95 its tread face flat.

6. A shoe heel comprising a deformable, resilient top section, normally of concavo-convex form and thicker at the edges than in the middle, having at its concave face a substantially inextensible reinforcing element, combined with a concavo-convex base section of substantially uniform thickness throughout, to produce a flat tread face and a concave 100 face conforming to the heel seat of a shoe. 105

In testimony whereof I have signed my name to this specification.

GEORGE E. WARREN.
